UNITED STATES PATENT OFFICE.

WILLIAM BARNUM COWLES, OF CLEVELAND, OHIO, ASSIGNOR TO THE
"LONG ARM" SYSTEM COMPANY, OF SAME PLACE.

HYDRAULIC SYSTEM FOR OPERATING RECIPROCATING MECHANISM.

SPECIFICATION forming part of Letters Patent No. 608,838, dated August 9, 1898.

Application filed December 17, 1897. Serial No. 662,349. (No model.)

To all whom it may concern:

Be it known that I, WILLIAM BARNUM COWLES, a citizen of the United States, residing at Cleveland, in the county of Cuyahoga and State of Ohio, have invented certain new and useful Improvements in Hydraulic Systems for Operating Reciprocating Mechanism; and I do hereby declare the following to be a full, clear, and exact description of the invention, such as will enable others skilled in the art to which it appertains to make and use the same.

My invention relates to improvements in hydraulic apparatus for opening and closing bulkhead-doors, hatches, ports, valves, gates, and other such devices, and while designed especially for use on shipboard it may be used advantageously in factories, large buildings, or any other place where such a system is necessary or desirable.

The combination of the system with a bulkhead-door is claimed, broadly, in my Patent No. 605,399, granted June 7, 1898, the application for which was concurrently pending herewith; but the system *per se*, without limitation to any particular form of device to be operated, is claimed, broadly, in this application.

The objects of my invention are, first, to construct an apparatus which shall be simple, durable, positive in its action, reliable, and not likely to get out of order, by means of which a series of mechanical devices situated at a distance from the operating-point may be all operated simultaneously in case of an emergency; second, to provide a system in which the power for operating a number of mechanical devices will be supplied to the said devices through a single main pipe and will be maintained at a predetermined pressure therein, and, third, to provide means at each device to be operated whereby the said device may be controlled at will.

Reference is had to the accompanying drawings, in which the same parts are indicated by the same letters throughout the several views.

Figure 1 represents a diagrammatic view of the primary system connected to an accumulator for supplying fluid-pressure to the main line and its branches. Fig. 2 represents a

front elevation of a vertically-sliding bulkhead-door with my improved means for opening and closing the same applied thereto. Fig. 3 represents a sectional elevation of the operating-valve and operating-cylinder. Fig. 4 represents a section along the line 4-4 of Fig. 3. Fig. 5 represents a horizontal section through the axis of the accumulator, parts being shown in elevation.

Referring now more particularly to Fig. 1, A represents a steam or other fluid pressure accumulator of any well-known form, A' being the steam or other fluid pressure cylinder, and A² the ram-cylinder thereof. This accumulator may be called the "central station" or source of power and control, hereinafter referred to.

The steam-piston A⁴ has a hollow piston A⁵, which passes through the packing-glands A⁶ and enters the ram-cylinder A², and as the said hollow piston-rod is forced into the ram-cylinder the pressure of the fluid in the ram-cylinder A² will be equal to the pressure of the steam multiplied by the area of the steam-piston A⁴ and divided by the area of the closed end of the hollow piston-rod A⁵, thus neglecting leakage and friction.

Steam or other fluid pressure is supplied to the steam-cylinder A' through a pipe a from any suitable source. For convenience of description the pipe a and cylinder A' will be hereinafter called the "steam-pipe" and "steam-cylinder," although any other suitable fluid under pressure, such as compressed air, may be admitted to the same. This pipe a is preferably provided with reducing-valves a' and a² before entering the steam-cylinder. The first reducing-valve a' is set to reduce the steam-pressure to a predetermined limit—90 as, for instance, a pressure of one hundred pounds to the square inch—and the second reducing-valve is set to reduce the steam-pressure to about one-half the pressure allowed to pass through the first valve, or about fifty pounds to the square inch, which latter is the usual pressure for working the system.

The accumulator-pumps A³ are supplied with steam through a pipe a³ from the interior of the steam-cylinder A', and the supply of steam to the pumps may be automatically regulated in any well-known way. The pipe

a^3 is preferably perforated, as shown in Fig. 5, and projects through suitable packing in the piston A^4 , the advantages of which arrangement are well known in the art and 5 form no part of my present invention. These pumps A^3 when in operation are supplied with fluid through the pipes a^4 , which fluid is forced through the pipe a^5 into the ram-cylinder A^2 , whence it is forced through the 10 distributing-main B and its branches b to the several doors, hatches, ports, valves, or other devices to be operated, as shown in Fig. 2. A branch pipe a^6 leads from the steam-pipe a between the two reducing-valves a' a^2 to the pipe a^3 thus serving as a "by-pass" from 15 between the reducing-valves to the cylinder and pumps, or this branch pipe a^6 may lead to the steam-cylinder, as indicated in dotted lines at a^6 , Fig. 1, which is preferable, as it 20 maintains the governing during the emergency working. A valve a^7 is placed in the pipe a^6 , and when this valve is closed the steam entering the cylinder and pumps must pass through both of the reducing-valves a' 25 and a^2 , where its pressure is reduced in two steps to the usual working pressure. When the valve a^7 is open, the steam will be admitted to the cylinder and pumps at the 30 pressure with which it leaves the first reducing-valve, thus immediately increasing (generally doubling) the fluid-pressure in the main B and its branches b . The object of increasing or doubling the pressure in the 35 main B is to close all the bulkhead-doors or operate all the devices at once, as in case of accident to the ship or in any other emergency, and the means for closing the said doors or operating the devices by this increase of pressure will be hereinafter 40 described.

The valve a^7 is opened or closed either by hand or by any other suitable mechanism, preferably by means of a power-cylinder C , which forms a part of a primary system, such 45 as is shown and described in Letters Patent of the United States, granted to me July 21, 1896, No. 564,474, and may be briefly described as follows: The two cylinders C and C' of equal piston displacement are connected with each 50 other by the pipes $c c$, which pass through the six-way valve C^2 , located in the circuit between said cylinders. These cylinders and pipes are filled with fluid under pressure from the supply-pipe c^3 , connected either to the 55 ram-cylinder A^2 , as shown in dotted lines at C^3 in Fig. 1, or to any other source of fluid-pressure. c^4 represents the discharge-pipe. The piston of the cylinder C is connected with the lever of the valve a^7 , and 60 when this piston is operated to open or close the said valve the fluid forced from one end of its cylinder will cause a corresponding travel of the piston in the cylinder C' , which travel may be indicated by a pointer c' , attached to the piston-rod and moving over a scale c^2 . The six-way valve C^2 is provided 65 with a lever C^3 and handle C^4 , by means of

which the valve may be turned to admit fluid-pressure to either end of the power-cylinder C to open or close the valve a^7 , the piston in the telltale-cylinder C' moving at the same time to indicate that the power-cylinder is doing its work.

The primary system just described constitutes the emergency portion of the whole system. If on board ship, the six-way valve C^2 is placed on the bridge, in the conning-tower, or in any other suitable place, and if on shore wherever preferable, and when it is desired to close all the doors or operate all the devices a simple movement of the lever C^3 will cause the power-cylinder C to open the valve a^7 and throw the double pressure into the main B and its branches and close all the bulkhead-doors or operate all the devices, as 85 will now be described.

In Fig 2 of the drawings I have illustrated a vertically-sliding bulkhead-door as the preferred form of door for use with the present system; but it will be obvious that this system may be readily adapted to operate various forms of doors, gates, ports, or valves other than those herein specifically described.

In Figs. 2 and 3, D represents the door, which slides vertically in the ways or guides E . A cylinder F is secured to the door D , as by means of the plates f and bolts f' , and extends the whole length of and a little above the door. Within this cylinder is arranged a hollow piston F' , from which a hollow piston-rod F^2 extends through the upper cylinder-head F^4 , which is provided with the usual packing f^4 , and the said pipe is secured to the bulkhead some distance above the door by the bracket and socket X' , which latter is bolted to the bulkhead, as at x . The hollow piston-rod F^2 opens into the cylinder above the piston through the vents or ports f^2 . Within the hollow piston rod or pipe F^2 is arranged a smaller pipe F^3 , leaving an annular space f^0 between the inner and outer pipes, and the latter pipe F^3 extends through the piston and opens into the lower part of the cylinder, as at f^3 . The upper ends of the two pipes F^2 and F^3 are secured in a double elbow G , which also receives the ends of the two pipes $H H'$, which convey the fluid-pressure to the cylinder F and conduct the fluid from the pipe H through a passage g to the inner pipe F^3 and the fluid from the pipe H' through the passage g' to the outer pipe F^2 . Thus when the fluid under pressure is admitted to the pipe H and released from the pipe H' it will pass through the inner pipe F^3 to the lower part of the cylinder F , thus forcing the said cylinder down and causing the door which is secured to the cylinder to close, while if fluid be admitted through the pipe H' and released from the pipe H it will enter the cylinder F above the piston-rod and will raise the door. The flow of fluid through the pipes $H H'$ is controlled by the operating-valve K and the parts connected thereto. This operating-valve K consists of a casing K' , bored out in the direc-

tion of its axis to form the valve-chamber k^0 to receive the valve-plug I, which latter is made to fit snugly in the valve-chamber k^0 . The casing K' is secured in position by bolts 5 through the holes k' . The valve-plug I is operated by the hand-lever I' and is preferably held in the central position by springs I². (Shown in Fig. 2 and described in detail in my Patent No. 605,399, granted June 7, 1898.)

10 The several pipes are connected to the casing by the couplings L. The pipes H and H' enter opposite sides of the casing, respectively, and open into passages h h' , leading to the valve-chamber k^0 . The branch pipe b from the pressure-main B enters through its coupling L and opens into the passage b' in the valve-easing leading into the valve-chamber k^0 at right angles to the openings h h' . The exhaust-passage h^2 opens into the valve-chamber k^0 on the opposite side to the passage b' and communicates with the exhaust-pipe H², which is connected by its coupling L to the lower side of the casing K' on one side of the pipe H'. On the other side of the pipe H' a pipe H³ opens into a passage h^3 in the valve-easing leading into the passage b' . The pipe H² leads to a reservoir M, into which the fluid from the cylinder F is discharged after having done its work, and this reservoir M is 25 provided with an overflow-pipe m, leading to waste or returning to a tank connected with the pipe a⁴. The latter method is preferable, as making a return system of piping and saving the fluid or liquid; or the pipe may lead 30 to the bilge or to any other convenient place. The pipe H³ leads to an auxiliary source of supply, such as a hand-pump M' of any suitable construction, which may be used to force the fluid from the reservoir M through the 35 pipe H' and valve K to the cylinder F to open or close the door by hand-power from either side of bulkhead or to operate the other device or devices should the main line become disabled.

40 The valve-plug I is provided with two ports or passages i i' , which open through the sides of the valve-plug, the said openings being at a distance of ninety degrees apart, so that when the plug is turned to one position one 45 of the ports, as i , will form a communicating passage between the passages b and h and the other port i' will form a communicating passage between the passages h' and h^2 . In this position the fluid from the main B will 50 pass from the pipe b, through the pipes H and F³, to the lower part of the cylinder to close the door or operate the other device, while the fluid from the upper part of the cylinder will escape through the pipes F² and H', the 55 passage h' in the valve-easing, the port i' in the valve, and the passage h^2 to the exhaust-pipe H², and thence to the reservoir M. When the plug is turned the other way, the 60 passage b' from the main B will be opened into the passage h' , so that the fluid will pass through the pipes H' and F² to the top of the cylinder above the piston F', and thus force

the said cylinder upward and open the door, the fluid from the lower part of the cylinder passing through the pipes F³ and H, the passage h , port i , and passage h^2 to the exhaust-pipe H² and reservoir M.

70 It will be obvious that the valve-plug I may be operated by hand by means of the hand-lever I'; but to provide for the operation of the system from the central station, as by the lever C³, the valve-casing is provided with two chambers K² and K³, one of which, K², communicates with the passage b' through an opening k^2 , which opening is kept normally closed by a check-valve K⁴, held upon its seat by a spring k⁴, the tension of which spring is sufficient to hold the said check-valve closed against the usual pressure in the main B and its branches b, but is not 80 strong enough to resist increased pressure should it be turned on in case of emergency. A passage k⁶ connects the chamber K² with the passage h , so that should the increased pressure be turned on while the valve K is 85 closed the check-valve K⁴ would be forced open and the increased fluid-pressure would pass through the chamber K² to the pipe H and thence to the cylinder F and close the door. The chamber K³ communicates with the passage h^2 through an opening k^3 , closed by a check-valve K⁵, held upon its seat by a spring k⁵, which spring is strong enough to hold the check-valve closed against the usual pressure in the system, but not strong enough 90 to resist the increased pressure when thrown on, so that when the increased pressure is exerted in the lower end of the cylinder to close the door the increased pressure in the exhausting end of the cylinder will force the 95 check-valve K⁵ open and allow the exhaust fluid to pass into the chamber K³, which is open, to the exhaust-pipe H².

100 From the foregoing it will be seen that the normal position of the valve-plug I is as shown in Fig. 3—i.e., with all its ports closed—thus holding the door or other device from movement. When it is desired to open or close the door or operate the device, the handle I' is turned to the right or left, as the case 105 may be, thus admitting the pressure to the cylinder F to open or close the door. Should it be desirable to close all the doors or operate the other devices, as in case of an emergency, the increased fluid-pressure is 110 turned on at the accumulator, as hereinbefore described, and this will force the check-valves K⁴ open and, passing to the cylinders F, will close the doors, the exhaust-pressure forcing the check-valves K⁵ open and escaping 115 therethrough.

120 Should it be necessary to check the movement of one or more of the doors or other devices or to open one while being closed by the increased pressure, the handle I' may be 125 turned in the usual direction for opening the door and held in this position. This will open the ports in the valve-plug I and will turn the whole pressure into the upper end

of the cylinder R to open the door. During this short interval for liberating an attendant caught by the emergency-closing action a slight amount of fluid will escape through 5 the valves K⁴ and K⁵, for both at this time have their upper sides in connection with the overflow-pipe H²; but this cannot prevent at least the ordinary pressure being available to open the door, and the slight amount of 10 waste fluid can do no harm. When the attendants have all passed from the compartment, if the handle be released, when it will be restored to the central position by the springs I² or be turned in the opposite direction, this will turn the whole pressure into 15 the lower end of the cylinder, and the door will be closed.

While I have shown the herein-described hydraulic system as applied to a bulkhead-door, it will be obvious that the same may 20 be applied to operating hatch-covers, gate-valves, slides, or other devices where like reciprocating motion is desired.

It will be obvious that various modifications 25 might be made in the herein-described system and apparatus which could be used without departing from the spirit of my invention.

Having thus described my invention, what I claim, and desire to secure by Letters Patent 30 of the United States, is—

1. In a hydraulic system of the character described, the combination with a receptacle adapted to contain a body of fluid under pressure, of an emergency-cylinder, with piston therein, pipes respectively connected to each end of said cylinder and adapted to contain fluid under pressure, a fluid-pressure pipe and an exhaust-pipe, and means for connecting the pipe from one end of said cylinder to the fluid-pressure pipe and from the other end of the cylinder to the exhaust-pipe, or vice versa, means for varying the pressure of the fluid in said receptacle controlled by the fluid in said pipes, and emergency mechanism operated by the change of pressure of the fluid in said receptacle, substantially as described.

2. In a hydraulic system of the character described, the combination with a receptacle 50 adapted to contain a body of fluid under pressure, of an emergency-cylinder, with piston therein, pipes respectively connected to each end of said cylinder and adapted to contain fluid under pressure, a fluid-pressure pipe and an exhaust-pipe, and means for connecting the pipe from one end of said cylinder to the fluid-pressure pipe and from the other end of the cylinder to the exhaust-pipe, or vice versa, a fluid-pressure main connected to said 55 receptacle, branch pipes leading from said main, mechanism operated by the fluid in said branch pipes, means operated by the piston in the emergency-cylinder for varying the fluid-pressure in said receptacle and in said fluid-pressure main, and emergency mechanism connected to the branch pipes and operated

by the change of pressure in said fluid-pressure main, substantially as described.

3. In a hydraulic system of the character described, the combination with a receptacle 70 adapted to contain a body of fluid under pressure, of an emergency-cylinder, with piston therein, pipes respectively connected to each end of said cylinder and adapted to contain fluid under pressure, a fluid-pressure pipe and an exhaust-pipe, and means for connecting the pipe from one end of said cylinder to the fluid-pressure pipe and from the other end of the cylinder to the exhaust-pipe, or vice versa, a fluid-pressure main connected to said 75 receptacle, branch pipes leading from said main, mechanism operated by the fluid in said branch pipes, a releasing-valve mechanism connected to each of said branch pipes and adapted to control the flow of fluid through 80 said branch pipe and thus to control the mechanism operated thereby, means operated by the piston in the emergency-cylinder for varying the fluid-pressure in said receptacle and in said fluid-pressure main, and emergency 85 mechanism connected to the branch pipes and operated by the change of pressure in said fluid-pressure main, substantially as described.

4. In a hydraulic system of the character described, the combination with a ram-cylinder 90 adapted to contain a body of fluid under pressure, and a fluid-pressure main leading therefrom and a steam-cylinder for exerting pressure upon said fluid, with valves for regulating the said pressure, of an emergency-cylinder, with piston therein, pipes respectively connected to each end of said emergency-cylinder and adapted to contain fluid under pressure, a fluid-pressure pipe and an exhaust-pipe, and means for connecting the pipe from one end of said emergency-cylinder to the fluid-pressure pipe and from the other end of the emergency-cylinder to the exhaust-pipe, or vice versa, means operated by the 95 piston in the emergency-cylinder for increasing the pressure of the steam in the steam-cylinder, and emergency mechanism operated by the increased pressure in the ram-cylinder, substantially as described.

5. In a hydraulic system of the character described, the combination with a ram-cylinder 100 adapted to contain a body of fluid under pressure, and a steam-cylinder for exerting pressure upon said fluid, with valves for regulating the said pressure, of an emergency-cylinder, with piston therein, pipes respectively connected to each end of said emergency-cylinder and adapted to contain fluid under pressure, a fluid-pressure pipe and an exhaust-pipe, and means for connecting the pipe from one end of said emergency-cylinder to the fluid-pressure pipe and from the other end of the emergency-cylinder to the exhaust-pipe, or vice versa, means operated by the piston 105 in the emergency-cylinder for increasing the pressure of the steam in the steam-cylinder, 110 substantially as described.

and emergency mechanism operated by the increased pressure in the ram-cylinder, substantially as described.

6. In a hydraulic system of the character described, the combination with a ram-cylinder adapted to contain a body of fluid under pressure, and a steam-cylinder for exerting pressure upon said fluid, with valves for regulating the said pressure, of an emergency-cylinder, with piston therein, pipes respectively connected to each end of said emergency-cylinder and adapted to contain fluid under pressure, a fluid-pressure pipe connected to said ram-cylinder and an exhaust-pipe, and a six-way valve for connecting the pipe from one end of said emergency-cylinder to the fluid-pressure pipe and from the other end of the emergency-cylinder to the exhaust-pipe, or vice versa, a fluid-pressure main, leading from the ram-cylinder, branch pipes leading from said main, mechanism operated by the fluid in said branch pipes, and mechanism operated by the piston in the emergency-cylinder for increasing the pressure of the steam in the steam-cylinder, and emergency mechanism operated by the increased pressure in the ram-cylinder, substantially as described.

7. In a hydraulic system of the character described, the combination with a receptacle adapted to contain a body of fluid under pressure, of an emergency-cylinder, with piston therein, pipes respectively connected to each end of said cylinder and adapted to contain fluid under pressure, a fluid-pressure pipe and an exhaust-pipe, and a six-way valve for connecting the pipe from one end of said cylinder to the fluid-pressure pipe and from the other end of the cylinder to the exhaust-pipe, or vice versa, means for varying the pressure of the fluid in said receptacle controlled by the fluid in said pipes, and emergency mechanism operated by the change of pressure of the fluid in said receptacle, substantially as described.

8. In a hydraulic system of the character described, the combination with a ram-cylinder adapted to contain a body of fluid under pressure, and a steam-cylinder for exerting pressure upon said fluid, with valves for regulating the said pressure, of an emergency-cylinder, with piston therein, pipes respectively connected to each end of said emergency-cylinder and adapted to contain fluid under pressure, a fluid-pressure pipe and an exhaust-pipe, and means for connecting the pipe from one end of said emergency-cylinder to the fluid-pressure pipe, and from the other end of the emergency-cylinder to the exhaust-pipe, or vice versa, a fluid-pressure main leading from the ram-cylinder, branch pipes leading from said main, mechanism operated by the fluid in said branch pipes and mechanism operated by the piston in the emergency-cylinder for regulating the pressure in the steam-cylinder and so controlling the pressure in all of said branch pipes, substantially as described.

9. In a hydraulic system of the character described, the combination with a ram-cylinder adapted to contain a body of fluid under pres-

sure, and a steam-cylinder for exerting pressure upon said fluid, with valves for regulating the said pressure, of an emergency-cylinder, with piston therein, pipes respectively connected to each end of said emergency-cylinder and adapted to contain fluid under pressure, a fluid-pressure pipe connected to said ram-cylinder and an exhaust-pipe, and a six-way valve for connecting the pipe from one end of said emergency-cylinder to the fluid-pressure pipe and from the other end of the emergency-cylinder to the exhaust-pipe, or vice versa, a fluid-pressure main, leading from the ram-cylinder, branch pipes leading from said main, mechanism operated by the fluid in said branch pipes, and mechanism operated by the piston in the emergency-cylinder for regulating the pressure in the steam-cylinder and so controlling the pressure in all of said branch pipes, substantially as described.

10. In a hydraulic system of the character described, the combination with a ram-cylinder adapted to contain a body of fluid under pressure, and a steam-cylinder for exerting pressure upon said fluid, with valves for regulating the said pressure, of an emergency-cylinder, with piston therein, pipes respectively connected to each end of said emergency-cylinder and adapted to contain fluid under pressure, a fluid-pressure pipe connected to said ram-cylinder and an exhaust-pipe, and means for connecting the pipe from one end of the emergency-cylinder to the fluid-pressure pipe and from the other end of the emergency-cylinder to the exhaust-pipe, or vice versa, a fluid-pressure main leading from the ram-cylinder, branch pipes leading from said main, reciprocating mechanism operated by the fluid in said branch pipes and mechanism operated by the piston in the emergency-cylinder for controlling the pressure in the ram-cylinder and so all of said branch pipes, substantially as described.

11. In a hydraulic system of the character described, the combination with a ram-cylinder adapted to contain a body of fluid under pressure, and a steam-cylinder for exerting pressure upon said fluid, with valves for regulating the said pressure, of an emergency-cylinder, with piston therein, pipes respectively connected to each end of said emergency-cylinder and adapted to contain fluid under pressure, a fluid-pressure pipe and an exhaust-pipe, means for connecting the pipe from one end of said emergency-cylinder to the fluid-pressure pipe and from the other end of the emergency-cylinder to the exhaust-pipe, or vice versa, and means for indicating the flow of fluid through said pipes, a fluid-pressure main leading from the ram-cylinder, branch pipes leading from said main, reciprocating mechanism operated by the fluid in said branch pipes and mechanism operated by the piston in the emergency-cylinder for controlling the pressure in all of said branch pipes, and emergency mechanism connected

to each of said branch pipes and operated by increase of pressure in the branch pipe, substantially as described.

12. In a hydraulic system of the character described, the combination with a ram-cylinder adapted to contain a body of fluid under pressure, and a steam-cylinder for exerting pressure upon said fluid, with valves for regulating the said pressure, of an emergency-cylinder, with piston therein, pipes respectively connected to each end of said emergency-cylinder and adapted to contain fluid under pressure, a fluid-pressure pipe and an exhaust-pipe, and means for connecting the pipe from one end of said emergency-cylinder to the fluid-pressure pipe and from the other end of the emergency-cylinder to the exhaust-pipe, or vice versa, a fluid-pressure main connected to said ram-cylinder, branch pipes leading from said main, mechanism operated by the fluid in said branch pipes, mechanism operated by the piston in the emergency-cylinder for controlling the pressure in said fluid-pressure main and in all of said branch pipes, and emergency mechanism connected to each of said branch pipes and operated by increase of pressure in the fluid-pressure main, substantially as described.

13. In a hydraulic system of the character described, the combination with a source of fluid-pressure, of an accumulator adapted to contain fluid under pressure and itself operated by fluid from the source of fluid-pressure, means for regulating the pressure of the fluid in the accumulator, a fluid-pressure main leading from the accumulator, branch pipes from said main, reciprocating mechanism operated by the fluid in said branch pipes, and releasing-valve mechanisms located in each of said branch pipes and separately operated by hand at low pressures and simultaneously automatically operated at high pressures, substantially as described.

14. In a hydraulic system of the character described, the combination with a ram-cylinder adapted to contain a body of fluid under pressure, and a steam-cylinder for exerting pressure upon said fluid, with valves for regulating the said pressure, of an emergency-cylinder, with piston therein, pipes respectively connected to each end of said emergency-cylinder and adapted to contain fluid under pressure, a fluid-pressure pipe and an exhaust-pipe, and means for connecting the pipe from one end of said emergency-cylinder to the fluid-pressure pipe and from the other end of the emergency-cylinder to the exhaust-pipe, or vice versa, a fluid-pressure main connected to said ram-cylinder, branch pipes leading from said main, devices to be operated provided with cylinders operated by the fluid in said branch pipes, a valve operated by the piston in the emergency-cylinder for controlling the pressure in the steam-cylinder and thus regulating the pressure in the ram-cylinder and in all of said branch pipes, and a hand-operated releasing-valve connected to

each of said branch pipes and adapted to control the flow of fluid through said branch pipe and to control the mechanism operated thereby, substantially as described.

15. In a hydraulic system of the character described, the combination with a source of fluid-pressure, of an accumulator adapted to contain fluid under pressure and itself operated by fluid from the source of fluid-pressure, means for regulating the pressure of the fluid in the accumulator, a fluid-pressure main leading from the accumulator, a branch pipe from said main, mechanism operated by the fluid in said branch pipe, and releasing-valve mechanism located in said branch pipe and operated by hand at low pressures and automatically operated at high pressures, substantially as described.

16. In a hydraulic system of the character described, the combination with a source of fluid-pressure, of an accumulator adapted to contain a body of fluid under pressure, a plurality of reducing-valves for regulating the admission of fluid-pressure from said source to said accumulator, a by-pass opening from between said reducing-valves into said accumulator, a valve controlling said by-pass, means for operating said valve, and mechanism operated by the fluid-pressure from the accumulator, substantially as described.

17. In a hydraulic system of the character described, the combination with a source of fluid-pressure, of an accumulator adapted to contain a body of fluid under pressure, a plurality of reducing-valves for regulating the admission of fluid-pressure from said source to said accumulator, a by-pass opening from between said reducing-valves into said accumulator, a valve controlling said by-pass, means for operating said valve, a fluid-pressure main connected to said accumulator, branch pipes connected to said main, and mechanism operated by the fluid-pressure in said branch pipes, substantially as described.

18. In a hydraulic system of the character described, the combination with a source of fluid-pressure, of an accumulator adapted to contain a body of fluid under pressure, a plurality of reducing-valves for regulating the admission of fluid-pressure from said source to said accumulator, a by-pass opening from between said reducing-valves into said accumulator, a valve controlling said by-pass, means for operating said valve, a fluid-pressure main connected to said accumulator, branch pipes connected to said main, and reciprocating mechanism operated by the fluid-pressure in said branch pipes, substantially as described.

19. In a hydraulic system of the character described, the combination with a source of fluid-pressure, of an accumulator adapted to contain a body of fluid under pressure, a plurality of reducing-valves for regulating the admission of fluid-pressure from said source to said accumulator, a by-pass opening from between said reducing-valves into said accu-

- 5 mulator, a valve controlling said by-pass, means for operating said valve, a fluid-pressure main connected to said accumulator, branch pipes connected to said main, and a hand-operated releasing-valve in each of said branch pipes, substantially as described.

10 20. In a hydraulic system of the character described, the combination with a source of fluid-pressure, of an accumulator adapted to contain a body of fluid under pressure, a plurality of reducing-valves for regulating the admission of fluid-pressure from said source to said accumulator, a by-pass opening from between said reducing-valves into said accumulator, a valve controlling said by-pass, means for operating said valve, a fluid-pressure main connected to said accumulator, branch pipes connected to said main, reciprocating mechanism operated by the fluid-pressure sure in said branch pipes, and a hand-operated releasing-valve in each of said branch pipes, substantially as described.

26. In a hydraulic system of the character described, the combination with a source of fluid-pressure, of an accumulator adapted to contain fluid under pressure and itself operated by fluid from the source of fluid-pressure, a plurality of reducing-valves interposed between the source of fluid-pressure and the accumulator, with a by-pass from between said valves to the accumulator with a valve controlling said by-pass for regulating the pressure of the fluid in the accumulator, a fluid-pressure main leading from the accumulator, branch pipes from said main, mechanism operated by the fluid in said branch pipes, and releasing-valve mechanisms located in each of said branch pipes and separately operated by hand at low pressures and simultaneously automatically operated at high pressures, substantially as described.

31 36 41 46 51 56 61 66 71 76 81 86 91 96 101 106 111 116 121 126 131 136 141 146 151 156 161 166 171 176 181 186 191 196 201 206 211 216 221 226 231 236 241 246 251 256 261 266 271 276 281 286 291 296 301 306 311 316 321 326 331 336 341 346 351 356 361 366 371 376 381 386 391 396 401 406 411 416 421 426 431 436 441 446 451 456 461 466 471 476 481 486 491 496 501 506 511 516 521 526 531 536 541 546 551 556 561 566 571 576 581 586 591 596 601 606 611 616 621 626 631 636 641 646 651 656 661 666 671 676 681 686 691 696 701 706 711 716 721 726 731 736 741 746 751 756 761 766 771 776 781 786 791 796 801 806 811 816 821 826 831 836 841 846 851 856 861 866 871 876 881 886 891 896 901 906 911 916 921 926 931 936 941 946 951 956

27. In a hydraulic system of the character described, the combination with a source of fluid-pressure, of an accumulator adapted to contain a body of fluid under pressure, a plurality of reducing-valves interposed between the source of fluid-pressure and the accumulator, with a by-pass from between said valves to the accumulator with a valve controlling said by-pass for regulating the pressure of the fluid in the accumulator, a fluid-pressure main leading from the accumulator, branch pipes from said main, reciprocating device to be operated, a cylinder and piston one of which is fast to the reciprocating device and the other to the framework surrounding the same, and the movable part being operated by the fluid in said branch pipe, and releasing-valve mechanism located in said branch pipe and operated by hand at low pressures and automatically operated at high pressures, substantially as described.

32 37 42 47 52 57 62 67 72 77 82 87 92 97 102 107 112 117 122 127 132 137 142 147 152 157 162 167 172 177 182 187 192 197 202 207 212 217 222 227 232 237 242 247 252 257 262 267 272 277 282 287 292 297 302 307 312 317 322 327 332 337 342 347 352 357 362 367 372 377 382 387 392 397 402 407 412 417 422 427 432 437 442 447 452 457 462 467 472 477 482 487 492 497 502 507 512 517 522 527 532 537 542 547 552 557 562 567 572 577 582 587 592 597 602 607 612 617 622 627 632 637 642 647 652 657 662 667 672 677 682 687 692 697 702 707 712 717 722 727 732 737 742 747 752 757 762 767 772 777 782 787 792 797 802 807 812 817 822 827 832 837 842 847 852 857 862 867 872 877 882 887 892 897 902 907 912 917 922 927 932 937 942 947 952 957

- rality of reducing-valves for regulating the admission of fluid-pressure from said source to said accumulator, a by-pass opening from between said reducing-valves into said accumulator, a valve controlling said by-pass, means for operating said valve, and reciprocating mechanism operated by the fluid-pressure from the accumulator, substantially as described.
28. In a hydraulic system of the character described, the combination with a source of fluid-pressure, of an accumulator adapted to contain a body of fluid under pressure, a plurality of reducing-valves for regulating the admission of fluid-pressure from said source to said accumulator, a by-pass opening from between said reducing-valves into said accumulator, a valve controlling said by-pass, a hydraulic system for operating said valve, and reciprocating mechanism operated by the fluid-pressure from the accumulator substantially as described.
29. In a hydraulic system of the character described, the combination with a source of fluid-pressure, of an accumulator adapted to contain a body of fluid under pressure, a pair of reducing-valves for regulating the admission of fluid-pressure from said source to said accumulator, a by-pass opening from between said reducing-valves into said accumulator, a valve controlling said by-pass, a hydraulic system operated by pressure from the accumulator for operating said valve, a fluid-pressure main connected to said accumulator, branch pipes connected to said main, and mechanism operated by the fluid-pressure in said branch pipes, substantially as described.
30. In a hydraulic system of the character described, the combination with a source of fluid-pressure, of an accumulator adapted to contain a body of fluid under pressure, a plurality of reducing-valves for regulating the admission of fluid-pressure from said source to said accumulator, a by-pass opening from between said reducing-valves into said accumulator, a valve controlling said by-pass, a hydraulic system operated by pressure from the accumulator for operating said valve, a fluid-pressure main connected to said accumulator, branch pipes connected to said main, and reciprocating mechanism operated by the fluid-pressure in said branch pipes, substantially as described.
31. In a hydraulic system of the character described, the combination with a fluid-pressure main and a branch pipe leading therefrom, and means for raising and lowering the pressure in said main, of mechanism operated by the pressure in said branch pipe, and releasing-valve mechanism located in said branch pipe, and adapted to be operated by hand at all pressures and to be operated automatically at high pressures only substantially as described.
32. In a hydraulic system of the character described, the combination with a fluid-pressure main and a branch pipe leading therefrom, and means for raising and lowering the pressure in said main, of reciprocating mechanism operated by the pressure in said branch pipe, and a releasing-valve mechanism located in said branch pipe, and adapted to be operated by hand at all pressures and to be operated automatically at high pressures only, substantially as described.
33. A releasing-valve, for use in apparatus of the character described, comprising a valve-casing with two passages therethrough crossing at right angles, and a perforated plug at the intersection of said passages, the said passages being also provided with lateral ports or openings, spring-operated valves closing said lateral ports against normal pressures but yielding to high pressures, passages and pipes leading from the rear of said spring-operated valves to the mechanism to be operated, and pipes leading from the valve-casing to the source of pressure and to the exhaust, substantially as described.
34. In a hydraulic system of the character described, the combination with a closed receptacle adapted to contain a body of fluid under pressure, an emergency cylinder and piston with mechanism operated by said piston for increasing the pressure of the fluid in said receptacle, and emergency mechanism operated by the increase of said fluid-pressure, substantially as described.
35. In a hydraulic system for operating reciprocating mechanism, the combination with a supply-pipe from the source of fluid-pressure, and an exhaust-pipe, of a fixed hollow piston-rod with separate passages, therethrough to the upper and lower sides of the piston, respectively, a cylinder secured to the mechanism to be operated, double pipes connecting the passages in the piston-rod to the supply-pipe, and a four-way valve for connecting one of the passages in the piston-rod to the supply-pipe, and the other to the exhaust, or vice versa, with means for operating this valve by hand at all pressures, with auxiliary means for admitting fluid-pressure operated automatically at high pressures only, substantially as described.

In testimony whereof I affix my signature in presence of two witnesses.

WILLIAM BARNUM COWLES.
